US00D860915S

(12) **United States Design Patent** (10) Patent No.: **US D860,915 S**
Tang (45) Date of Patent: **** Sep. 24, 2019**

(54) **BIKE MOUNTED HOLDER FOR A MOBILE DEVICE**

(71) Applicant: **Li Ding Tang**, Beijing (CN)

(72) Inventor: **Li Ding Tang**, Beijing (CN)

(**) Term: **15 Years**

(21) Appl. No.: **29/632,940**

(22) Filed: **Jan. 11, 2018**

(51) **LOC (12) Cl. 12-11**

(52) **U.S. Cl.**

USPC **D12/407**

(58) **Field of Classification Search**

USPC D12/407, 114, 400, 415, 406, 177, 178, D12/223; D14/253, 252, 251, 447, 432

(57) **CLAIM**

The ornamental design for a bike mounted holder for a mobile device, as shown and described.

DESCRIPTION

FIG. 1 is a front right-top perspective view for a bike mounted holder for a mobile device, showing my new design;

FIG. 2 is a front perspective view of FIG. 1 thereof;

FIG. 3 is a rear perspective view of FIG. 1 thereof;

FIG. 4 is a left side perspective view of FIG. 1 thereof;

FIG. 5 is a right side perspective view of FIG. 1 thereof;

FIG. 6 is a top perspective view of FIG. 1 thereof; and,

FIG. 7 is a bottom perspective view of FIG. 1 thereof.

1 Claim, 7 Drawing Sheets
